(57) **CLAIM**

The ornamental design for a display screen or portion thereof with animated graphical user interface of X-ray CT apparatus as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with an animated graphical user interface of an X-ray CT apparatus of a first image of our new design;

FIG. 2 is a front view of a display screen or portion thereof with an animated graphical user interface of an X-ray CT apparatus of a second image of our new design; and,

FIG. 3 is a front view of a display screen or portion thereof with an animated graphical user interface of an X-ray CT apparatus of a third image of our new design.

The outermost dashed broken line illustrates a display screen that forms no part of the claimed design. The shaded half-tone overlay illustrates elements of the animated graphical user interface that form no part of the claimed design. The subject matter in this patent includes a process or period in which an image changes into another image. The process or period forms no part of the claimed design.
